New York, N. Y., a corporation of New York

Application December 13, 1946, Serial No. 716,161

17 Claims. (Cl. 112—235)

1

This invention relates to presser devices for sewing machines, and more particularly to devices of this type having pairs of articulated presser feet.

An object of the invention is to provide an improved articulated-foot type of presser device in which the relative positions of the presser feet when raised from the work may be controlled so as to suit various work requirements.

Another object of the invention is to provide an improved articulated-foot type of presser device in which the relative pressures of the presser feet and positions of the latter when engaging a workpiece may be readily adjusted and controlled to adapt the presser device to various types of work, speeds of sewing, etc., and also to provide such a device in which the retracting or lifting movements of the presser feet in surmounting a cross seam or other obstruction are not adversely affected or impaired.

A further object of the invention is to provide an improved presser device as above in which the control of the presser feet, either when raised or lowered and engaging a workpiece, is governed by a single, simple adjustment.

A still further object of the invention is to provide an improved presser device as above in which the controlling is automatically accomplished during use of the machine without requiring extra operations on the part of the operator.

A feature of the invention is the provision of a presser device as above which is extremely simple in construction and economical to manufacture.

In accomplishing the above objects, according to the invention, a presser device is provided comprising a front presser foot and a rear presser foot which are pivotally connected together by rocker arms, the latter being pivotally mounted on the lower end of a spring-urged presser bar carried by the sewing head of the machine.

Each presser foot may thus have independent pivotal movement on the rocker arms, and by virtue of the latter being themselves pivoted, may have up and down movement which is virtually translational in nature.

The raising and lowering of the presser bar is effected by a lifter which has a laterally extending arm adapted to engage the lower end of the bar. Between the said laterally extending arm and the rear presser foot of the presser device a compression coil spring is mounted, and by this organization pressure in excess of that supplied by the presser bar is transmitted to the said rear foot.

A novel and simple adjustable mechanism is provided by which, through connection with the frame of the machine, the relative pressures of the presser feet on a workpiece may be controlled

2

and changed as well as the relative positions of the presser feet. This novel mechanism also functions to control the relative positions of the feet when the latter are in lifted position, disengaged from a workpiece.

In the embodiment of the invention illustrated herein this mechanism comprises a simple tilt lever which is pivotally carried on an eccentric stud or pivot mounted on the lower end of the presser bar. One end of the lever engages one of the rocker arms which carry the presser feet, the point of engagement being adjacent the pivot for the front presser foot, and the other end of the lever is adapted to engage a second arm which is provided on the lifter device for the presser bar.

The eccentric pivot and the tilt lever carried thereby are so arranged that when the lifter is holding the presser bar in elevated position, the tilt lever may be engaged by the second arm of the lifter, and by adjusting the eccentric pivot the lever may be made to change the positions of the rocker arms, and therefore the relative positions of the presser feet. The range of adjustment of the tilt lever and eccentric pivot is such that the front presser foot may be maintained in a position considerably below the rear presser foot and vice versa, or the presser feet may be maintained in various adjusted positions intermediate these extremes, including the position where both are on the same level.

Also, when the lifter is operated so that the presser bar is dropped to cause the presser feet to engage a workpiece, the arrangement of the tilt lever and eccentric pivot is such that the relative pressures of the presser feet may be varied, as well as the relative positions of these, and thus the presser device may be adjusted to best suit a particular type of work or a particular speed of feed, etc.

By making the tilt lever cooperable with the lifter, the control of the pressures and positions of the presser feet is automatically accomplished by the actuation of the lifter, and therefore the operator is relieved from going through an additional operation in order to make effective the control of the presser feet.

The action of the tilt lever is such that the retracting or lifting movements of the presser feet in surmounting a cross seam or other obstruction in the work may take place in the normal manner, and in fact may be facilitated by proper adjustment of the tilt lever, since such adjustment may relieve the front presser foot of some of its pressure, if this is found desirable.

By the provision of the tilt lever and the eccentric pivot therefor, a single adjustment, effected by turning the pivot one way or the other, is all that is necessary to obtain the desired control

of the presser feet when in both the raised and lowered positions.

The control of the presser feet is thus accomplished by few parts, namely, the eccentric pivot, the tilt lever and the actuating arm on the lifter which is cooperable with the tilt lever, and these parts are simple in construction and economical to fabricate and to install.

Other features and advantages will hereinafter appear.

In the accompanying drawings:

Figure 1 is a side elevation, enlarged, of the improved presser device of the invention, a part only of the lifter mechanism being shown, and the throat plate of the sewing machine being shown in section. The presser device is being maintained in raised position by the lifter, and the adjustment of the device is such that both the front and rear presser feet are on the same level.

Fig. 2 is a view like Fig. 1 but with the adjustment altered so that the front presser foot is raised higher than the rear presser foot.

Fig. 3 is a view like Figs. 1 and 2 but with the adjustment such that the front presser foot is lower than the rear presser foot.

Fig. 4 is a side elevation of the presser device in lowered position wherein the presser feet can engage a workpiece, the adjustment of the device corresponding to the adjustment of Fig. 1.

Fig. 5 is a view like Fig. 4 but with the adjustment of the device corresponding to the adjustment of Fig. 2.

Fig. 6 is a front elevation of the presser device as shown in Fig. 5, the eccentric pivot and the tilt lever carried thereby being shown in section, and

Fig. 7 is a view like Figs. 4 and 5 but with the adjustment of the device corresponding to the adjustment of Fig. 3.

As shown, the presser device of this invention comprises a presser bar 10 carrying at its lower end a bracket 11 having a split collar 12 and, secured to the latter, a yoke portion 13 from which a pair of arms 14 depend. The arms 14 pivotally carry rocker levers or arms 15 which at their front ends pivotally mount a front presser foot 16 and at their rear ends a rear presser foot 17.

By this construction the front and rear presser feet are individually pivotally movable on the rocker arms 15, and the front foot 16 may be raised and the rear foot 17 lowered or vice versa by pivotal movement of the rocker arms on the depending arms 14.

The presser device is associated with a machine having the usual frame F, throat plate T, feed dogs D and needle N, Fig. 1.

For the purpose of raising and lowering the presser bar 10 and the presser feet 16 and 17 carried thereby a lifter is provided in the form of a collar 18 carried on a shaft 19 which latter is secured to the machine frame (not shown), the collar being actuated by a driving arm 20 and having a lateral extension 21 carrying a flat arm 22 (see Fig. 4, broken lines) the remote end 23 of which extends under the bracket 11 for engagement with the underside thereof. Between the arm 23 and the rear presser foot 17 a compression coil spring 24 is mounted, one end of the spring encompassing a depending pin 25 secured to the arm end 23, and the other end of the spring being received in a recess 26 in the rear presser foot 17.

It will be seen that when the driving arm 20 of the lifter is forced downward, the arm 22 thereof will be raised and, after engaging the un-

dersurface of the bracket 11, will raise the latter and the presser bar 10, together with the presser feet carried thereby, and will maintain this assemblage in raised position as shown in Figs. 1 through 3. When the driving arm 20 of the lifter is raised to releasing position, the spring pressure which is normally exerted on the presser bar 10, as is conventional in sewing machines, will force the presser bar and bracket 11, and the presser foot assemblage carried thereby down into work-engaging position, as shown in Figs. 4 through 7.

According to this structure the compression spring 24 augments the pressure applied to the rear presser foot 17 by the rocker arms 15. The pressure exerted by the presser bar 10 is divided substantially equally between the presser feet 16 and 17 when the latter are engaging a workpiece; however, because of the spring 24 the pressure of the rear presser foot 17 on the workpiece is increased beyond this by the amount of the spring pressure.

According to the present invention a novel and simple mechanism is provided for controlling the relative positions of the presser feet 16 and 17 when the latter are in their elevated positions as shown in Figs. 1 through 3, and for controlling the relative pressures which the presser feet exert on a workpiece, and the relative positions of the said feet when the latter are in their lowered positions as shown in Figs. 4 through 7.

This mechanism, in the embodiment of the invention illustrated herein, comprises a tilt lever 27 which is carried on an eccentric collar 28, the latter being secured by a screw 29 to one of the depending arms 14 of the bracket 11. The foremost end of the tilt lever 27 is bent laterally at right angles to form a flange 30, the underedge of which is adapted to engage the upper surface 31 of the adjacent rocker arm 15. The other end of the tilt lever 27 is somewhat hook-shaped and has a bill 32 which is adapted to be engaged by a laterally extending arm 33 projecting from the collar 18 of the lifter.

Referring to Figs. 1 through 3, the parts are so organized and shaped that when the lifter is maintaining the presser bar 10 and the presser foot assemblage carried thereby in raised position, adjustment of the eccentric collar 28 will cause the foremost end of the tilt lever 27 to shift the rocker arms 15 against the expanding action of the compression spring 24, the hook-like end of the tilt lever being backed up and prevented from moving by the lifter arm 33. For example, when the eccentric collar or pivot 28 is in its lowermost position as shown in Fig. 3, the foremost end of the tilt lever 27 will depress the said ends of the rocker arms 15 to a considerable extent, thereby lowering the front presser foot 16 and raising the rear presser foot 17, the latter compressing the spring 24. When the eccentric collar 28 is in its uppermost adjusted position as shown in Fig. 2 the foremost end of the tilt lever 27 will allow the front ends of the rocker arms 15 to be raised under the expanding action of the spring 24, thereby enabling the latter to maintain the front presser foot 16 in a higher position than the rear presser foot 17. An intermediate adjustment of the eccentric collar 28, as shown in Fig. 1, causes the presser feet 16 and 17 to be maintained at the same level.

These different raised, relative positions of the presser feet 16 and 17 are of advantage when handling different types and sizes of work materials.

The tilt lever 27 and eccentric collar 28 also operate to control the relative pressures exerted by the front and rear presser feet on a workpiece, and to control the relative positions of these feet when in operative position as shown in Figs. 4 through 7. For example, when the eccentric collar 28 is adjusted in its lowermost position as shown in Figs. 3 and 7, and as the lifter is actuated to drop the presser bar and presser feet, the end 32 of the tilt lever will remain in engagement with the lifter arm 33 and will cause the lever to limit the position of the rocker arms 15 so that the rear presser foot 17 is maintained raised above the front presser foot 16. In such circumstance, the rear presser foot 17 does not engage the work, the sole engagement being effected by the front presser foot. By changing the adjustment of the eccentric collar 28 the rear presser foot may be lowered with respect to the front presser foot from the position shown in Fig. 7, and may be caused to engage a workpiece with varying amounts of pressure.

The adjusted positions of the eccentric collar 28 as shown in Figs. 1, 2, 4 and 5, are such that when the presser feet are lowered and in engagement with a workpiece, they exert their normal pressures thereon and are not under the control of the tilt lever 27. In this circumstance it will be seen that the rear presser foot 17 will exert a greater pressure on the work than the front presser foot 16, the additional pressure being supplied by the compression spring 24, which is backed up by the lateral arm 22 of the lifter.

It will be obvious that by proper adjustment of the eccentric collar 28 the additional pressure of the rear presser foot 17 may be lessened, until it becomes practically zero, whereupon both the presser feet will be made to press against a workpiece with equal pressures. As the eccentric collar 28 is further adjusted, the front presser foot will be made to exert the greater pressure on the work, until the extreme condition is reached as shown in Fig. 7, wherein all of the pressure on the work is exerted by the front presser foot.

By this organization therefore, a very flexible and minute control of the relative pressures and positions of the presser feet may be had, to suit various types of workpieces and speeds of sewing, etc.

It will be noted that, considering Fig. 7 wherein the tilt lever 27 is exerting control, when the front presser foot 16 encounters an obstruction such as a cross seam or other projecting part in a workpiece, the said foot may raise and surmount the said obstruction in the normal manner. The raising of the front presser foot 16 in surmounting a cross seam causes the bracket 11 and presser bar 10 to be raised approximately half the amount of the presser foot. During such movement both the tilt lever 27 and the rocker arms 15 will fulcrum about their respective pivots. The rear ends of the rocker arms 15 will act as if they were anchored and therefore not move, since the upper end 32 of the tilt lever 27 is immovably backed up by the lifter arm 33 and since the front ends of the tilt lever 27 and rocker arm 15 will remain in engagement during the surmounting movement of the front presser foot. This is analogous to the action obtained if the tilt lever 27 is adjusted so as to not exert control during the sewing operation, as for instance with the adjustment of the eccentric collar shown in Figs. 4 and 5. It will be seen that, from these

figures, as the front presser foot 16 raises to surmount a cross seam, the rear ends of the rocker arms 15 will remain stationary during the surmounting movement due to the rear presser foot immovably resting on the work prior to the cross seam reaching it. Thus the surmounting action of the front presser foot 16 is substantially the same, whether the tilt lever 27 is controlling the relative pressures and positions of the presser feet, or whether the lever is inoperative for such control.

The control of the presser feet either while in lowered work-engaging position or while in raised position out of engagement with the work is governed by a single adjustment, that of turning the eccentric collar 28, and the said collar may be locked in any newly adjusted position by tightening of the screw 29. It will be seen that during the operation of the machine, and after the proper adjustment of the eccentric collar 28 has been made, the control of the presser feet is automatically accomplished by the actuation of the lifter which raises and lowers the presser bar and presser foot assemblage.

The above control of the presser feet is accomplished by few parts, namely the tilt lever 27, eccentric collar 28 and lifter arm 33, and these parts are of simple and economical construction and may be readily installed without requiring a great deal of additional space.

Variations and modifications may be made within the scope of this invention and portions of the improvements may be used without others.

I claim:

1. In a sewing machine, a frame; a presser bar; a pair of presser feet pivotally carried by the presser bar and located one ahead of the other; and adjustable means varying the pivotal relation of the feet to the presser bar for controlling the relative pivotal positions of the presser feet with respect to the presser bar.
2. In a sewing machine, a frame; a presser bar; a pair of presser feet pivotally carried by the presser bar and located one ahead of the other; and adjustable means including a member connected with the frame and cooperable with the feet for controlling the relative pivotal positions of the presser feet when the latter are in lifted position out of engagement with a workpiece.
3. In a sewing machine, a frame; a presser bar; a pair of presser feet pivotally carried by the presser bar and located one ahead of the other; and adjustable means including a member connected with the frame for controlling the relative pivotal positions of the feet and the pressures exerted on a workpiece by the presser feet when the latter are engaging the workpiece.
4. In a sewing machine, a frame; a presser bar; a pair of presser feet carried by the presser bar and located one ahead of the other; and adjustable means including a member connected with the frame and having a lifter for the presser bar, an eccentric pivot on the presser bar, and a lever carried by the pivot and engaging the said lifter for controlling the relative positions of the presser feet.
5. In a sewing machine, a presser bar; a pair of tandem-mounted presser feet carried by the presser bar; a lifter for the presser bar; and adjustable means including an eccentric pivot carried by the presser bar and including a lever carried by the pivot and engageable with the lifter, for controlling the relative positions of the presser feet.
- 75 6. In a sewing machine, a frame; a spring-

urged presser bar on the frame; a pair of presser feet pivotally carried by the presser bar and located one ahead of the other; a lifter mounted on the frame for raising and lowering the presser bar; and adjustable means carried on the presser bar to vary the pivotal relation of the feet with respect to the presser bar and cooperable with the lifter, for controlling the relative pivotal positions of the presser feet with respect to the presser bar when the presser bar is in lowered or sewing position.

7. In a sewing machine, a frame; a spring-urged presser bar on the frame; a pair of presser feet pivotally carried by the presser bar and located one ahead of the other; a lifter mounted on the frame for raising and lowering the presser bar; and adjustable means carried on the presser bar and cooperable with the lifter, for controlling the relative pressures exerted on a workpiece by the presser feet when the presser bar is in lowered or sewing position.

8. In a sewing machine, a frame; a spring-urged presser bar on the frame; a pair of presser feet pivotally carried by the presser bar and located one ahead of the other; a lifter mounted on the frame for raising and lowering the presser bar; and adjustable means carried on the presser bar and cooperable with the lifter, for increasing the pressure on a workpiece by the front presser foot relative to the rear presser foot when the presser bar is in lowered or sewing position.

9. In a sewing machine, a frame; a spring-urged presser bar on the frame; a rocker arm carried by the presser bar at the lower end thereof; a pair of presser feet pivotally connected to the rocker arm and located one ahead of the other; a lifter mounted on the frame for lowering and raising the presser bar; and adjustable means carried on the presser bar and cooperable with the lifter, the said means engaging the rocker arm for controlling the position of the latter and the relative positions of the presser feet when the presser bar is in lowered or sewing position.

10. In a sewing machine, a frame; a spring-urged presser bar on the frame; a rocker arm carried by the presser bar at the lower end thereof; a pair of presser feet pivotally connected to the rocker arm and located one ahead of the other; a lifter mounted on the frame for lowering and raising the presser bar; an eccentric pivot on the presser bar; and a lever carried by the pivot and engaging the lifter and the rocker arm for controlling the relative positions of the presser feet.

11. In a sewing machine, a frame; a spring-urged presser bar on the frame; a rocker arm carried by the presser bar at the lower end thereof; a pair of presser feet pivotally connected to the rocker arm and located one ahead of the other; a lifter mounted on the frame for lowering and raising the presser bar; a pivot on the presser bar, adjustable thereon to different positions; and a lever carried by the pivot and at one end engaging the lifter to be lifted thereby, the other end of the lever engaging the rocker arm for controlling the position of the latter and the relative positions of the presser feet.

12. In a sewing machine, a presser bar; a lifter for the presser bar; a rocker arm carried by the presser bar at the lower end thereof; a pair of presser feet pivotally connected to the rocker arm

and located one ahead of the other; and means including an adjustably mounted member cooperable with the rocker arm for maintaining the front presser foot either higher than, at the same level as, or lower than the rear presser foot, depending on the adjustment of the said member, when both presser feet are in lifted position out of engagement with a workpiece.

13. In a sewing machine, a presser bar; a lifter for the presser bar; a rocker arm carried by the presser bar at the lower end thereof; a pair of presser feet pivotally connected to the rocker arm and located one ahead of the other; and means including a spring connected with the lifter and with the rear presser foot, and including an adjustably mounted member cooperable with the rocker arm and lifter for maintaining the front presser foot either higher than, at the same level as, or lower than the rear presser foot, depending on the adjustment of the said member, when both presser feet are in lifted position out of engagement with a workpiece.

14. In a sewing machine, a presser bar; a rocker arm carried by the presser bar at the lower end thereof; a pair of presser feet pivotally connected to the rocker arm and located one ahead of the other; and means connected with the frame and including an adjustably mounted member for maintaining the front presser foot either higher than, at the same level as, or lower than the rear presser foot, depending on the adjustment of the said member, when both presser feet are in lifted position out of engagement with a workpiece.

15. In a sewing machine, a frame; a presser bar; a pair of presser feet pivotally carried by the presser bar and located one ahead of the other; means cooperable with one of the presser feet for impressing a yielding supplemental pressure thereon; and adjustable means including an adjustable pivot and a member connected with the frame for controlling the relative pivotal positions of the presser feet under the supplemental pressure.

16. In a sewing machine, a pair of tandem-mounted presser feet; a lifter for said feet; means connected with the lifter and cooperable with one of the presser feet for impressing a yielding pressure thereon; and adjustable means cooperable with the lifter for controlling the relative positions of the presser feet.

17. In a sewing machine, a presser bar; a pair of tandem-mounted presser feet carried by the presser bar; a lifter for the presser bar; means connected with the lifter and cooperable with one of the presser feet for impressing a yielding pressure thereon; and adjustable means including an eccentric pivot carried by the presser bar and including a lever carried by the pivot and engageable with the lifter, for controlling the relative positions of the presser feet.
